UNITED STATES PATENT OFFICE.

WILLIAM J. CIPRA, OF CLEVELAND, OHIO.

COLLAR.

1,239,563.

Specification of Letters Patent. Patented Sept. 11, 1917.

Application filed October 23, 1916. Serial No. 127,227.

To all whom it may concern:

Be it known that I, WILLIAM J. CIPRA, a citizen of the United States, residing at Cleveland, in the county of Cuyahoga and 5 State of Ohio, have invented certain new and useful Improvements in Collars, of which the following is a specification.

This invention relates to apparel collars, and has as its primary object to provide a 10 collar which may be attached to the ordinary shirt neck band without the use, however, of buttons either for the purpose of attaching the collar or for closing the said neck band at the front.

15 Another aim of the invention is to provide an apparel collar having at one side of its front, means for not only attaching the collar to the neck band of a shirt, but to so construct and arrange this means that it will 20 serve also as a substitute for the collar button ordinarily employed at the front of the neck band.

The invention also aims to provide novel 25 and efficient means for connecting the ends of the collar at the front thereof, which means may serve also as a supporting means for the necktie applied to the collar.

In the accompanying drawings:—

Figure 1 is a plan view of an apparel collar embodying the present invention;

Fig. 2 is a vertical sectional view through the front portion of the collar;

Fig. 3 is a similar view taken also through the front of a shirt neck band and illustrating the manner in which the collar is connected with the neck band at the front of the latter;

Fig. 4 is a view similar to Fig. 3, but taken through the back of the collar and the 40 back of the neck band.

In the drawings, the numeral 1 indicates the band of the collar, which band is provided with a terminal flap 2 corresponding to the long flap of the ordinary collar and 45 with a flap 3 which corresponds to the short flap of an ordinary collar. The lower edge of the band at the rear side of the band is cut away, as indicated by the numeral 4, and within the cut away portion is provided 50 with an attaching tab 5 approximately triangular in shape and connected with the said edge by means of a relatively narrow shank portion 6. As stated, the tab 5 is substantially triangular and it, therefore, 55 has a relatively narrow entering end or point and the portions of the upper edge of

the said tab at the opposite sides of the shank 6 afford locking shoulders 7 which when the tab has been inserted through the buttonhole 8 at the back of the shirt neck 60 band, which is indicated by the numeral 9, will engage the upper side of the said buttonhole thereby preventing separation of the collar from the neck band. By reference to Fig. 1 of the drawings it will be observed 65 that the attaching tab 5 is located substantially within the cut away portion 4 and that the shoulders 7 occupy substantially the same position as the rear buttonhole in the ordinary collar. While, as stated, the at- 70 taching tab 5 is substantially triangular in form it is preferable that its shoulders 7, or, in other words, its upper edge portions, be inclined downwardly and inwardly toward the shank 6 so as to further insure against 75 separation of the tab from the neck band after having been inserted through the buttonhole 8.

The flap 2 of the collar is provided with a buttonhole, indicated by the numeral 10, the 80 purpose of which will be presently explained. The flap 3 is formed in its lower edge with a cut away portion 11 narrower than but corresponding to the cut away portion 4 at the back of the band and within the 85 cut away portion 11, the said flap 3 is provided with an attaching tab 12 substantially of the same shape as the attaching tab 5, the tab 12 having shoulders 13 corresponding to the shoulders 7 and having a shank 14 corre- 90 sponding to the shank 6. The tab 12 is designed to be inserted through the buttonholes at the front of the shirt neck band which buttonholes are indicated by the nu- 95 meral 15 and by reference to Fig. 3 of the drawings it will be understood that as the shank 14 extends through both buttonholes the neck band will be held closed without the employment of the ordinary collar-button and that, furthermore, the tab 12 will 100 serve as a means for attaching or connecting one end of the collar with the said shirt band. The flap 3 is further formed with an incision 16 which extends downwardly from the upper edge of the said flap and along a 105 curved line in the direction of the lateral edge of the flap and the formation of this incision results in a locking tab 17 which, due to the fact that the incision extends along a curved line, projects or extends upwardly and at an angle toward the inner end of the 110 flap 3. The tab 17 is so located that after

- the collar has been applied in the manner heretofore described the flap 2 thereof may be brought into overlapping relation to the flap 3 as in applying the ordinary collar and 5 the tab 17 may be inserted through the buttonhole 10 in the manner shown in Fig. 2 of the drawings, thereby locking the ends of the collar in overlapped relation. It will be understood, of course, that inasmuch as the 10 locking tab 17 projects upwardly after its insertion through the buttonhole end, a necktie may be engaged over the said tab and be thus supported against slipping downwardly with relation to the collar.
15. Having thus described the invention, what is claimed as new is:
1. An article of wearing apparel having a neck encircling portion provided at its ends with flaps to be overlapped, one of said flaps 20 having a longitudinal slit and the other flap being provided with a tab for insertion upwardly and outwardly through the said slit,

the last-mentioned flap having a shouldered attaching tab at its lower portion, the shoulders being inclined toward the shank of the 25 tab.

2. A collar having its band provided at one end with a flap having a slit formed therein, said slit extending longitudinally of the band, the band at its other end having a 30 flap provided in its upper edge with a downwardly extending incision providing a tab extending upwardly and toward the flap and adapted to pass upwardly and outwardly through the said longitudinally extending slit in the first-mentioned flap, the 35 lower edge of the second-mentioned flap inwardly of the said incision being cut away at spaced points to provide a downwardly projecting shouldered tab for insertion 40 through the buttonholes at the front of a shirt neck band.

In testimony whereof I affix my signature.

WILLIAM J. CIPRA. [L.S.]
